DECORATIVE RIBBON

William C. Protz, Manitowoc, Wis., assignor to
 National Tinsel Manufacturing Company,
 Manitowoc, Wis., a corporation of Wisconsin

Application August 24, 1936, Serial No. 97,672

6 Claims. (Cl. 41—21)

The present invention relates to a decorative ribbon or the like for use in tying packages or for other decorative purposes, and more particularly to a decorative ribbon made of transparent or translucent material and having contiguous areas of varying shades or degrees of transparency.

The use of transparent ribbon or ribbon like material for tying packages such as Christmas presents, store purchases, etc., is well known today. In many instances these ribbons are colored, oftentimes by incorporating a pigment in the material during its manufacture or by coating the material with a colored ink or like material.

In some instances attempts have been made to produce a ribbon having contiguous bands of varying shades by coating the material with varied shades of colored ink or by securing separate strips of material thereto by use of suitable adhesives. Neither of these methods have been satisfactory and both methods have been costly, and involved.

It is accordingly a primary object of the present invention to produce a novel vari-shaded ribbon without the use of inks of different colors or the use of separate strips secured to one another as by adhesives.

A further object of the present invention resides in the provision of a novel vari-shaded ribbon formed from a single strip of material.

A still further object of the present invention resides in providing a novel transparent or translucent ribbon with contiguous vari-shaded areas by folding the material to form certain areas of darker shade or shades than the original strip.

Another object of the present invention resides in providing a novel ribbon having vari-shaded contiguous areas and reinforced exposed edges formed by folding a single strip of material in novel manner.

A further object of the present invention resides in crimping certain areas of a variegated transparent multi-ply ribbon in novel manner to enhance its attractiveness and improve the bond between the several plies.

Further objects will appear from the detailed description and appended claims when taken in connection with the accompanying drawing wherein:

Figure 1 is a cross-section through a strip of material folded in a preferred manner in accordance with the present invention.

Figure 2 is a cross-section through a completed ribbon made from the folded strip of Figure 1.

Figure 3 is a plan of the top surface of the ribbon of Figure 2 showing the vari-shaded areas or bands.

Figures 4 through 17 are alternately cross-sections and plans of strips embodying preferred variations in the manner of folding shown in Figures 1, 2 and 3.

Figure 18 is a cross-section through a strip folded in another preferred manner.

Figure 19 is a plan of the top surface of a ribbon showing the vari-shaded areas or bands formed by the manner of folding shown in Figure 18.

Figures 20 through 23 are alternately cross-section plans of strips embodying preferred variations in the manner of folding shown in Figure 18.

Figures 24 and 25 are cross-section and plan, respectively, showing a ribbon which has been crimped in accordance with the teachings of the present invention.

Figure 26 is a preferred modification of the ribbon of Figures 24 and 25 wherein the crimping is accomplished on a line with the borders of the ribbon.

With continued reference to the drawings wherein like reference numerals are used to indicate like parts throughout the several figures, reference numeral 8 indicates generally a strip of transparent material which is to be folded in accordance with the present invention.

Strip 8 may be any suitable transparent material such as regenerated cellulose, Glassine or other similar transparencies. The material preferably employed in the manufacture of the decorative ribbon produced by the present invention is the transparent regenerated cellulose products sold under the trade names "Cellophane" and "Sylphrap".

The edges 9 of strip 8 are initially folded downwardly and inwardly along lines 11 as seen at the left of Figure 1. Edges 9 are then folded along lines 12 to form areas 13 and return folded portions 14. Portions 14 are in turn folded at 15 around the initial fold lines 11 so that the edges 16 thereof will overlie the opposite or upper face 17 of strip 8 as seen in Figure 2.

The lines of folds 11, 12 and 15 are creased tightly during the folding operation or immediately thereafter and the several plies 13, 14 and 16 are pressed tightly together by any suitable means such as a pair of smooth rolls. The pressure of the rolls, due to the peculiar properties of the aforementioned regenerated cellulose material, is sufficient to assure the permanent bond.

ing of the several plies. If a material having a wax or cementitious coating is employed, heat may be applied to melt the wax or like material and cement the folds to one another.

5 If desired, a suitable colorless, transparent adhesive may be applied between the several plies and the ribbon may then be passed through suitable drying rolls in a manner well known in the art.

10 The completed ribbon 18 is shown in cross-section in Figures 2 and 3. From an inspection of these figures, it will be apparent that border areas or bands 19 of quadruple thickness are provided by the method of folding described.

15 These bands 19, due to the plurality of layers of the material, will be less transparent than the inner area or band 21. As a result ribbon 18 is characterized by having two different shades; namely, dark borders 19 and a lighter central area or band 21. This difference in degree of transparency, particularly when transparent, colored, regenerated cellulose having a pigment incorporated therein during its manufacture is used, produces an unusually attractive ribbon.

20 25 In order to illustrate the variegated appearance of the completed ribbon 18, the drawing has been shaded with oblique lines to represent the color green. The difference in the shades of the contiguous bands 19 and 21 has been simulated by using a greater number of shade lines for the darker areas or bands 19.

A second preferred manner of folding the strip 8 to produce a ribbon having two shades like that of Figures 1 through 3 is shown in Figures 35 4 and 5. In this embodiment of the invention the area 13 and return folded portion 14 on one edge of the strip, the right hand edge as seen in Figure 4, are formed in the manner previously described. The other edge or left-hand edge of 40 the strip is formed by folding edge area 22 in the opposite direction, i. e., over the upper surface of strip 8. Edge area 22 is then return folded in the manner previously pointed out in connection with area 13 to form return folded portion 45 23.

Portion 23 is then folded along line 24 around the original line of fold 11 so that the edge area 25 thereof overlies the undersurface of strip 8. Portion 14 is also folded along a line 21 so that 50 its edge area 25 overlies the upper surface 17 of strip 8. Preferably the width of areas 25 is such that the free edges thereof will terminate at the longitudinal center line of strip 8.

The ribbon 26 formed thereby, as a consequence, is made up of border areas or bands 27 (Figure 5) of four-ply thickness and a center area or band 28 of two-ply thickness. Ribbon 26 accordingly presents border bands 27 having the same shade as bands 19 and a central band 28 60 having a slightly deeper shade than band 21 of Figures 1, 2 and 3. The edges of the ribbon of this form of the invention are reinforced in the manner described in connection with the previous embodiment of the invention.

65 A still different manner of folding strip 8 to obtain the color characteristics described in connection with Figures 4 and 5 is shown in Figures 6 and 7. In this modification of the invention, 70 the areas 13 and 14 are formed in the manner described in Figures 1, 2 and 3. The edges 25 are formed by folding the edge areas of portions 14 so that they overlie upper surface 17 and abut at the longitudinal center line of strip 8. This form 75 of the invention, like that of Figures 4 and 5

forms four-ply border bands 27 and a two-ply central band 28.

Ribbon 26 of Figures 4 and 5 or 6 and 7 is characterized by dark borders 27 due to the four-ply layers and a lighter central area 28 due to 5 the two-ply layer. The only difference between these latter forms of the invention and Figures 1 through 3, insofar as the shade of the various bands is concerned, is that the central band 21 of Figures 1 through 3 is of a slightly lighter 10 shade than central band 28 of Figures 4 through 7.

Figures 8 and 9 of the drawing illustrate a still different manner of folding strip 8 to obtain the color characteristics described in connection with Figures 1 through 7. The areas 31 of strip 8 in this modification of the invention are folded downwardly and inwardly around lines 11. Areas 31 are of such width that their free edges abut at the longitudinal center line of 20 strip 8. Areas 31 are return folded around lines 33 to form intermediate portions 34 which overlie areas 31 and extend to the fold lines 11. The edge areas 35 of portions 34 are in turn folded upwardly around fold lines 11 and extend in 25 inwardly over top surface 17 of strip 8 as shown in Figure 8.

As a consequence of the above described folding operations, a ribbon 36 having border areas or bands 37 (Figure 9) of four-ply thickness and 30 central area or band 38 of three-ply thickness is formed. As in the previously described modifications of the invention, ribbon 36 is characterized by dark borders 37 and a central band 38 of slightly lighter shade than borders 37. 35

A further modified form of the invention is illustrated in Figures 10 and 11. In this form of the invention, areas 13 and 14 and 22, 23 and 25 are formed in the same manner as that described in Figures 4 and 5. In this form of the 40 invention, one intermediate portion, that is indicated by numeral 14 in Figure 10, is shorter than the other so that its edge area 16 is of a width equal to that of portion 14. Ribbon 39, formed by the instant manner of folding, has four-ply borders or bands 40 one of which is contiguous to a two-ply band 41 and the other to a one-ply band 42. Preferably bands 41 and 42 each extend outwardly from the center line and are of equal width. Ribbon 39 as seen in Figure 11 is characterized by three shades; namely, dark borders 40, slightly lighter band 41 contiguous to one border, and a still lighter band 42 contiguous to the other border. The exposed edges of ribbon 39 are reinforced due to their being folded as 50 pointed out in connection with the preceding 55 form of the invention.

Figures 12 and 13 illustrate a different method of folding strip 8 to obtain a ribbon having three shades. In these figures the areas 13 are folded 60 around lines 11 in the manner previously described in connection with Figures 1 through 3. Areas 13 are then folded along transverse lines 43 chosen so that the first ply formed by the folding operation extends a slightly greater distance 65 toward the transverse center line of strip 8 than the corresponding ply of Figures 1 through 3 but not as far as that of Figures 8 and 9. This folding operation provides a return folded portion 44 similar in function to portion 14 of Figures 1 70 through 7.

Portions 44 are in turn folded along lines 45 around initial fold lines 11 so that the edge areas 46 thereof will overlie the face 17 of strip 8 and will be approximately equal in width to 75

areas 16 of Figures 1 through 3. The completed ribbon 47, shown in Figure 13, provides four-ply border bands 48, a single ply central band 49 and three-ply intermediate bands 50. 5 Ribbon 47 is, accordingly, characterized by three shades; namely, dark borders 48, slightly lighter contiguous bands 50 and a still lighter central band 49. The exposed edges of ribbon 47 may be reinforced in the manner previously pointed out. 10 A further manner of folding strip 8 to produce a ribbon having three shades is illustrated in Figures 14 and 15. The areas 13, return folded portion 44 and areas 46a are formed in exactly the same manner as the areas 13, 44 and 46 of 15 Figures 12 and 13. The only difference between this form of the invention and that of Figures 12 and 13 is that areas 46a are wider, i. e. extend inwardly toward the center line of strip 8 a greater distance than do areas 46. Because 20 of this fact the four-ply border 48a of ribbon 47a formed by folding, as shown in Figures 14 and 15, is wider than the borders shown in the previously described forms of this invention and the central lightest area 49a is considerably reduced 25 in width.

Ribbon 47a, therefore, exhibits a strikingly different appearance characterized by three shades; namely, wide dark borders 48a, slightly narrower and lighter contiguous bands 50a, and a still 30 lighter central band 49a.

Another striking three-shaded ribbon is obtained by folding strip 8 in the manner shown in Figures 16 and 17. Areas 13 are formed by folding along lines 11 in the manner described 35 in Figure 1. Areas 13 are then folded back along lines 51 to form a return folded portion 52. Areas 13 are preferably slightly narrower than areas 13 of Figure 1 and return folded portion 52 extends beyond the fold lines 11 a distance approximately equal to the width of areas 13. Portion 52 is in turn folded back at 53 to 40 form overlapping areas 54 equal in width to areas 52. Areas 54 overlie fold lines 11 and surface 17 of strip 8.

Ribbon 55, resulting from the folding operations just described, is made up of edge bands 56 of two-ply thickness, contiguous band 57 of four-ply thickness and a central band 58 of one-ply thickness. This ribbon, accordingly, 45 presents an appearance characterized by light shaded border bands 56, a still lighter central band 58 and intermediate bands 57 of a comparatively dark shade.

If desired, the novel shaded ribbons of the 55 present invention may be produced without in any way disturbing the contour of surface 17. To this end strip 8 is folded in the manner shown in Figures 18 through 23.

As illustrated in Figures 18 and 19, strip 8 has 60 its areas 13 formed by folding along lines 11 in the manner heretofore described. Areas 13 are then folded upon themselves along lines 12 to form return folded portions 14. Portions 14, as shown in Figure 18, are exactly equal in width 65 to areas 13 and their edges coincide with the edges formed by fold lines 11. Ribbon 59, formed in this manner, provides three-ply border bands 60 and a single ply central band 61. This ribbon, accordingly, presents a two shade appearance 70 characterized by dark border bands 60 and a light central band 61.

Figures 20 and 21 illustrate a further two-shaded ribbon formed by folding strip 8 so that surface 17 remains undisturbed. As seen in these 75 figures, edge areas 31 are folded along lines 11

in the manner previously described in connection with Figures 8 and 9. Areas 31 are in turn folded along lines 33 to produce relatively short return folded portions 63.

Ribbon 64, resulting from the above described 5 folding operations, contains border bands 65 of two-ply thickness and a central band 66 of three-ply thickness. Ribbon 64 is, therefore, characterized by light border bands 65 and a dark central band 66. 10

Figures 22 and 23 illustrate the construction of a further two-shaded ribbon formed by folding strip 8 in the manner shown in Figures 18 and 19, i. e. without disturbing surface 17. In this connection strip 8 has its areas 13 formed by folding along lines 11 in the manner previously described. Areas 13 are then folded upon themselves along lines 12 to form return folded portions 68 which as seen in Figure 22 are of slightly less width than areas 13. Portions 68 are in turn folded along lines 69 to form inwardly directed portions 71 which abut along the longitudinal center line of strip 8. 15 20

Ribbon 72 formed in this manner provides two-ply border bands 73, four-ply intermediate 25 bands 74, and a two-ply central band 75. The exposed edges of ribbon 72 are reinforced in the manner previously described and the ribbon is characterized by border bands 73 and a central band 75 of a uniform light shade and intermediate bands 74 of a darker shade. 30

If desired any one of the finished ribbons may be rendered more attractive by suitably crimping the ribbon or any one or more of the shade bands by passing the ribbon through corrugated rollers. 35 Such a ribbon is illustrated in Figures 24 and 25 where the ribbon formed in Figures 1 through 3 has the band 19 crimped as indicated by the vertical lines 79. The crimping operation as seen from Figure 24 provides angularly disposed reflecting surfaces 81 which materially enhance the decorative appearance of the ribbon and more securely bonds the layers or plies of material. 40

In Figure 26, the crimping is done in the center of the ribbon. Not only does this method provide a ribbon of attractive appearance but it also is useful in bonding ribbons of the type shown in Figures 6, 20 and 22. Obviously, the methods of crimping on the borders or on the edges may be applied to any of the ribbons described, or if desired, the entire surface of the ribbons may be 45 crimped. 50

The invention may be embodied in other specific forms without departing from the spirit or essential characteristics thereof. The present 55 embodiments are therefore to be considered in all respects as illustrative and not restrictive, the scope of the invention being indicated by the appended claims rather than by the foregoing description, and all changes which come within 60 the meaning and range of equivalency of the claims are therefore intended to be embraced therein.

What is claimed and desired to be secured by 65 United States Letters Patent is:

1. A decorative ribbon formed from a single strip of colored transparent material comprising a dark border formed by four thicknesses of said strip and a lighter contiguous area formed by a single thickness of said strip. 70

2. A decorative ribbon formed from a single strip of colored transparent material comprising a dark border formed by four thicknesses of said strip, a lighter area contiguous said border formed of at least two thicknesses of said strip, and a 75

still lighter area contiguous said last mentioned area formed by one thickness of said material.

3. A decorative ribbon formed from a single strip of transparent material comprising a border of a certain shade, a contiguous band of a different shade, and a contiguous band of a still different shade, said border and said bands being formed by folding said strip to provide areas made up of a different number of plies of said strip.

4. The combination defined in claim 3 wherein said plies are bonded together by a layer of transparent adhesive material.

5. The combination defined in claim 3 wherein one or more of said areas are crimped to provide angularly disposed reflecting surfaces.

6. A decorative, vari-shaded ribbon formed from a single strip of colored transparent material comprising spaced parallel transparent borders of an intermediate relatively dark shade and a contiguous transparent area of a shade relatively lighter than said border, said contiguous area being formed by more than one ply of material and the border by a still greater number of plies of material.

WILLIAM C. PROTZ.
